APPARATUS FOR OPENING CLOGGED DRAINS

Robert E. Wallace, Sr., Smithfield, Ohio

Application August 27, 1952, Serial No. 306,633

4 Claims. (Cl. 4—256)

This invention relates, as indicated, to an apparatus for opening clogged drains, and, more particularly, to an apparatus which will move an obstruction through a drain by the hydraulic pressure of a water main or by an increased pressure if the pressure of the main is insufficient to dislodge the obstacle.

Drains and soil pipe, particularly those of the household variety, frequently become clogged by an obstruction either becoming lodged or building up therein. Such obstructions are usually easily broken up or dislodged by mechanical agitation as by a "snake" but often are in a location which is not accessible for agitation in this manner. In such case, it is sometimes necessary to remove the soil pipe or plumbing to get at and remove the clogging obstruction.

One of the principal objects of this invention is to provide an apparatus which utilizes the hydraulic pressure of the water main for breaking up or removing an obstruction in a drain, the water main being the household supply line.

A further object of the invention is to provide an apparatus of this character with an hydraulic ram for increasing the pressure of the water main.

A still further object is to provide apparatus which is operated by the pressure of the water main to produce an increased pressure which is utilized to open the drain.

To these and related ends, the preferred embodiment of the invention includes a conduit for introducing water under the pressure of the water main into the clogged drain. This conduit is provided with a seal for preventing the escape of the water under pressure which is so introduced into the drain. The preferred embodiment of the seal comprises a flexible rubber cylinder which is mounted concentrically of the conduit which is used to introduce water into the drain. The end of the conduit with the seal thereabout is introduced into the mouth of the clogged drain, and water is introduced under main pressure into the cylinder for expanding it into fluid sealing engagement with the internal surfaces of the drain. Water may then be introduced through the conduit into the drain and the seal will be effective to prevent the escape of such water so that the full pressure of the main will be effective against the clogging obstruction. In the event that such pressure is insufficient to break up or move the obstruction forwardly through the drain, the apparatus includes an hydraulic ram which is operated by the hydraulic pressure of the water main to produce an increased or greater pressure within the drain for the purpose of moving forward the clogging obstruction.

Other objects and advantages will become apparent from the following disclosure.

In the drawings there is shown a preferred embodiment of the invention. In this showing:

Fig. 1 is a sectional view illustrating an apparatus constructed in accordance with the principles of this invention in an operative position with respect to the entry opening of a drain;

2

Fig. 2 is a modified form of seal for use with the apparatus shown in Fig. 1; and

Figs. 3 and 4 respectively are sectional views showing other types of seals usable with the apparatus shown in Fig. 1.

Referring to Fig. 1, the numeral 1 designates the entry end of a drain or soil pipe containing the clogging obstruction to be cleared. To remove the obstruction, a fitting 2 is provided for introducing water into the drain 1. 10 The water is introduced through a conduit 3 which is threaded into one end of the fitting 2 and which is provided with a seal 4 thereabout to prevent escape of water from the drain.

The seal 4 comprises spaced metal end plates 5 and 6 secured in position on the conduit 3. The end plates 5 and 6 have sealing engagement with the ends of a rubber cylinder 7 which is thus mounted concentrically on the conduit 3. The end plate 5 is provided with a fitting 8 through which water may be introduced to the interior 15 of the cylinder 7 to expand such cylinder into sealing engagement with the interior of the drain 1 in which it is positioned. The exterior surface of the cylinder 7 is provided with annular ribs 9 which have roughened or serrated surfaces to increase their sealing frictional engagement with the drain 1.

The water for expanding the cylinder 7 is delivered to the apparatus through a fitting 10, conduit 11, fitting 12, and conduit 13, the latter conduit being connected to the entry fitting 8. Admission of water to the conduit 13 is controlled by a manually operable two-way valve 14 which may be operated to selectively connect or disconnect the conduit 13 with respect to the conduit 11. In the disconnect and off position of the valve 14, the conduit 13 is connected through a port 15 to the atmosphere.

30 A connection of the conduit 3 with the water supply conduit 11 is controlled by a two-way valve 16 having connect and disconnect positions for controlling the connection of the conduit 11 with the conduit 3. In the off or disconnect position of the valve 16, the conduit 3 is connected to the atmosphere through a port 17. A check valve 18, is arranged between the valve 16 and the conduit 11 to prevent reverse flow of water through the valve 16 and into the conduit 11.

35 To increase the pressure of the water being supplied to the drain 1, an hydraulic ram 20 is provided. The ram 20 comprises a cylinder 21 which is threaded into one end of the fitting 2 so that it forms in effect an extension of the conduit 3. A piston 22 is mounted in the cylinder 21 and has an enlarged head 23 which acts as an operating piston and reciprocates in a cylinder 24. The cylinder 24 is closed by a cap 25 having a stuffing box 26 through which a guide rod 27 slides. The opposite end of the guide rod is connected at 28 to the operating piston 23 for movement therewith. Cushioning springs 29 and 30 are mounted in opposite ends of the cylinder 24 for cushioning the extreme movements of the operating piston 23. The cylinder 24 has ports to the atmosphere at 31 so that air pockets or vacuum will not be formed in the space 32. The cap 25 is provided with a fitting 33 through which water may be admitted from the fitting 10, a two-way valve 34 being provided for controlling the connection of the fitting 10 with the cylinder 20. The valve 34 is provided with a port 35 to the atmosphere through which water may be exhausted from the cylinder 24 when it is disconnected from the water supply fitting 10.

40 In operation, the valves 14, 16 and 34 are moved to their off position before the seal 4 is inserted in the entry opening of a clogged drain 1, and in the off position of these valves, the conduit 3, cylinder 20, and interior of the rubber cylinder 7 will be connected with the atmosphere. After the seal 4 has been placed in an operative

position as illustrated in Fig. 1, the valve 14 is rotated manually to the position shown in Fig. 1 to admit water from the conduit 11 into the sleeve 7. The pressure of the water in the sleeve 7 expands the sleeve 7 and moves the ribs 9 into fluid sealing engagement with the interior surface of the drain 1. The valve 16 is then rotated to the position shown in Fig. 1 to deliver water from the supply conduit 11 to the conduit 3. When water ceases to flow into the conduit 3, the valve 14 is moved to its off position to connect the interior of the rubber cylinder 7 with the atmosphere through the conduit 13 and port 15. This will release the seal provided by the sleeve 7 to allow air to escape from the interior of the drain 1. When water begins to seep past the seal 4, the operator will know the drain 1 is filled with water, and will then rotate the valve 14 to the position illustrated in Fig. 1 to expand the sleeve 7 into sealing engagement with the interior surface of the drain 1. The full pressure of the water main will thus be effective on the interior of the drain 1, and this pressure will ordinarily be effective in most cases to move the clogging obstruction forward in the drain or to break it up so that it may be washed away.

In the event that the full pressure of the water in the main is ineffective to remove the clogging obstruction, the hydraulic ram 20 may be operated to increase the pressure within the conduit 3 and drain 1. Operation of the ram 20 is effected by first turning the valve 34 to its off position so as to connect the interior of the cylinder 24 with the atmosphere through the opening 35. With the valve 34 in its off position, pressure of the water in the fitting 2 against the end of the piston 22 is effective to move the piston 22 and piston 23 to the left as viewed in Fig. 1. When the piston 23 moves against the spring 29, the valve 34 is rotated to its connect position as shown in Fig. 1 to admit water through the fitting 33 to the interior of the cylinder 20. The pressure of the water main against the head of the piston 23 will increase the pressure of the water in the conduit 3 and drain 1, and will move the piston 23 to the right and force the body of water filling the cylinder 21 through the fitting 2 into the conduit 3. The check valve 18 prevents the escape of water during this operation of the piston 22. The pistons 22 and 23 have an area ratio of approximately 1 to 4 so that the ram 20 is effective to multiply the pressure within the conduit 3. The increased pressure within the conduit 3 will in most cases be effective to start the forward motion of clogging obstructions which are not effected by the normal pressure of the water main. The ram 20 may be operated back and forth as many times as desired by proper manipulation of the valve 34, the water within the cylinder 24 being exhausted through the port 35 in the off position of the valve 34. By observing the rod 27 and the amount thereof protruding from the stuffing box 26, the operator will know the relative position of the piston 23 in the cylinder 24 and will thus know when to operate the valve 34.

Fig. 2 shows a modified form of seal and delivery conduit for admitting water under pressure to a clogged drain. In this showing, the delivery conduit 3 is replaced by a heavy rubber hose 40, and the seal 4 is replaced by an expansible bellows-like seal 41. The seal 41 is comprised of a circular rubber bellows 42 attached to the hose 40 by end plates 43 and 44. The interior of the bellows 42 is connected by a conduit 45 to a fitting 46 which replaces the fitting 8 of Fig. 1 and is for connection to the water supply conduit 13. The entry end of the housing 40 is provided with a fitting 47 for attachment to the fitting 2 of Fig. 1. Except for the fittings 46 and 47, the parts of the structure shown in Fig. 2 are constructed entirely of rubber. In operation, when water under pressure is admitted through the conduit 45, the bellows 42 will expand into sealing engagement with a drain in the same manner as the rubber cylinder 7 of Fig. 1. The seal of Fig. 2 is particularly adapted for use

in clearing clogged commodes or other drain openings having a similar irregular shape.

The modifications illustrated in Figs. 3 and 4 are seals in the form of attachments for connection to the fitting 2 of Fig. 1. These modified forms of seals omit the expandible and fluid operated pressure seals shown in Figs. 1 and 2. Referring particularly to Fig. 3, the numeral 50 designates a threaded fitting which is connectable in the outlet opening of the fitting 2 of Fig. 1 in place of the conduit 3. At its discharge end, the fitting 50 is provided with a rubber cup 51 having side walls which are shaped somewhat in the form of a barrel and which have concave inner and outer surfaces in cross section as illustrated in Fig. 3. The end 52 of the rubber cup 51 may be pressed into engagement with the surface surrounding a drain opening, such as a conventional lavatory drain opening, to form a seal thereabout. Water under pressure from the fitting 2 of the Fig. 1 may then be forced into the lavatory drain opening and the seal provided by manual pressure against the cup 51 will prevent the water from escaping from the drain.

In Fig. 4, there is shown a pressure seal 60 which is fabricated from rubber and has a shape similar to the suction cups commonly used for opening clogged drains. The seal 60 is semispherical in shape and has an outer edge 61 which may be pressed into sealing engagement with a surface about a drain opening. It has a central opening 62 in which is mounted a fitting 63 which may be threaded into the outlet opening of the fitting 2 of Fig. 1. The seal 60 is particularly adapted for use in connection with drain openings in which the surface surrounding the drain is a curved surface or one of irregular contour.

While I have illustrated and described a preferred embodiment of my invention, it will be understood that this is merely by way of illustration, and that various changes and modifications may be made therein within the contemplation of the invention and under the scope of the following claims.

I claim:

1. In a hydraulic pressure booster device, in combination, an open ended cylinder having connecting portions of different diameters, a differential piston within the cylinder for reciprocal movement therein having a short continuous head portion disposed within the larger cylinder portion and a longer stem portion for movement within the smaller cylinder portion, an open ended continuation of said smaller cylinder portion extending a substantial distance outward beyond the limit of the path of movement of the piston stem portion, a sealing member mounted on the exterior of said cylinder continuation adjacent the outer end thereof for engagement within an opening in a receptacle which receives hydraulic pressure from the smaller cylinder portion through the continuation thereof, a water inlet on the periphery of said smaller cylinder continuation beyond the path of movement of the piston stem admitting water to the smaller cylinder portion and the continuation thereof, a conduit connecting the water inlet to a water supply line, a check valve in said conduit preventing water flow from the cylinder and its continuation to the water supply line, a closure for the open end of the larger cylinder portion, a water inlet in said closure member, a conduit connecting the latter water inlet to the water supply line, a manually operable valve in said latter conduit for selectively admitting water to the larger cylinder portion and draining water therefrom providing reciprocation of the piston under water pressure from the water supply line.

2. The hydraulic pressure booster as in claim 1 in which the sealing member is a hollow inflatable member having rigid end portions rigidly connected to the continuation of the smaller cylinder portion, an inlet on one of said inflatable member rigid end portions, a conduit connecting said inlet with a water supply line, and a valve in said conduit selectively admitting water to the

interior of the inflatable sealing member and draining such water therefrom.

3. The hydraulic pressure booster as in claim 2 wherein the inflatable sealing member comprises a pair of spaced rigid members secured to the cylinder continuation and of an outer dimension smaller than the receptacle opening, an expandible corrugated hollow member disposed between said spaced rigid members and having end portions connected to the spaced rigid members, each end portion of said corrugated member including in-turned substantially U-shaped portions permitting uniform radial movement of the corrugated portion of the sealing member from deflated to inflated position for effecting a uniform seal between the corrugated portion of the sealing member and the walls of the receptacle opening.

4. In a hydraulic pressure booster for opening clogged drains, the combination of an open ended cylinder having connecting chambers of different diameters, a differential piston within said cylinder for reciprocal movement therein having portions provided with a sliding fit within each chamber, the cylinder of smallest diameter having an open ended extension thereon to be received within the clogged drain, an inflatable sealing member mounted on the exterior of said extension adjacent the outer end thereof to be freely received within the drain when deflated, rigid end portions on the sealing member having fixed connections with said extension, a flexible extensible portion disposed between said sealing member end portions and connected thereto so as to provide substantially uniform radial expansion of the flexible extensible portion relative to the cylinder extension, a water inlet opening in one of said sealing member rigid end portions, a closure member for the larger end of said cylinder, a water inlet in said closure

admitting water to the larger cylinder chamber, a conduit connecting the inlet opening in the cylinder closure member to a fitting receiving a water supply line, a manually operable valve in said conduit selectively movable to admit water from the supply line to the cylinder and to cut off the water supply and water from the cylinder, a water inlet in the periphery of the cylinder extension between the extreme advanced position of the smaller end of the differential piston and the sealing member, a conduit connecting said cylinder extension inlet with the water supply line, a check valve in said conduit preventing flow of water from the cylinder extension to the water supply line, manually operable valve means in said second named conduit for selectively cutting off water from the supply line to said cylinder extension inlet, a conduit connecting the water supply line with the inlet in the rigid end portion of the sealing member independently of flow of water through either cylinder inlet, and manually operable valve means in said last named conduit for selectively controlling water flow in the conduit to inflate, deflate and hold the sealing member in inflated position.
